UNITED STATES PATENT OFFICE.

GEORGE P. ABORN, OF BROOKLINE, MASSACHUSETTS, ASSIGNOR TO WORTHINGTON
PUMP AND MACHINERY CORPORATION, A CORPORATION OF VIRGINIA.

ENGINE VALVE.

Application filed October 27, 1920. Serial No. 420,038.

To all whom it may concern:

Be it known that I, GEORGE P. ABORN, a citizen of the United States, residing at Brookline, county of Norfolk, and State of Massachusetts, have invented certain new and useful Improvements in Engine Valves, fully described and represented in the following specification and the accompanying drawings, forming a part of the same.

10 This invention relates to steam engines equipped with fluid actuated valves especially adapted for use in direct acting pumps, and particularly to a fluid actuated valve structure in which the main slide valve is moved by an auxiliary piston while free therefrom for movement toward and away from its seat and the auxiliary exhaust passes through the auxiliary piston and main valve to the exhaust cavity therein 20 for discharge with the main cylinder exhaust.

The object of this invention is to provide a cheap, efficient and durable valve mechanism of this type which shall not require packing to prevent leakage of live steam to the auxiliary exhaust passage.

In the drawings, which show two valve mechanisms embodying the preferred forms of the invention—

30 Fig. 1 is a section transversely of the steam cylinder showing one form of the invention;

Fig. 2 is a section on line 2—2 of Fig. 1;

Fig. 3 is a section longitudinally of the steam cylinder showing another form of the invention; and

Fig. 4 is a top plan view of the main slide valve shown in Fig. 3.

Referring to the drawings, the main engine cylinder A, within which operates the piston 10, is provided with a seat 11 for the auxiliary cylinder B having a central valve seat 12 supplied with the usual steam ports and passages 13, 14 for delivery of steam to 40 and from the opposite ends of the cylinder A, and an exhaust port and passage 15 connecting with the side exhaust outlet 16.

The auxiliary piston 17 comprises preferably two pistons cast integrally with a connecting portion 18 and is provided with a valve seat 19 for the auxiliary valve 20 which is actuated by rod 21 through suitable links and levers connected to the piston rod of the main piston 10. Suitable ports 1, 2

in the auxiliary valve seat 19, connect respectively with longitudinal passages 3, 4 extending through the auxiliary piston 17 to opposite ends thereof for passage of steam to and from the ends of the auxiliary cylinder B and are connected with exhaust port 60 and passage 5 through exhaust cavity 6 in the auxiliary valve 20.

The main valve 22, which is of the common D type, is provided with one or more projections which engage the central part of the auxiliary piston 17 so that the valve is moved by the piston while free therefrom for movement toward and away from its seat. The valve 22 has the usual exhaust cavity 23 adapted to connect one or the other 70 of the ports 13, 14 with the exhaust port 15 and is connected to the auxiliary exhaust port and passage 5 by suitable means now to be described and forming the features of my invention.

This means may advantageously be of the form shown in Figs. 1 and 2, in which main valve 22 is provided with two parallel spaced projections 24, 25 receiving between them the connecting portion 18 of the auxiliary piston 17, which is preferably rectangular throughout that portion between the projections, and is provided on each side with a pair of spaced flanges 26 adapted to move the main valve 22 as a unit with the auxiliary piston 17 and to allow vertical movement of the main valve. Auxiliary exhaust port and passage 5 connect with a horizontal port 9 on one side of the connecting portion 18 which registers with a port 7 80 on the inner side of the projection 25 connected to the main slide valve exhaust cavity 23 by a passage 8. To prevent vertical movement of the main valve 22 from decreasing the size of the auxiliary exhaust 90 passage below its normal capacity I preferably provide the ports 9 and 7 with flaring openings, as shown.

Suitable means is provided to assure steam tight engagement of the projection 25 and 100 the corresponding side of the auxiliary piston which may be of the form shown, in which spring 27 is placed between the projection 24 and the corresponding side of the auxiliary piston and is held in position by 105 a screw 28 secured in the projection 24.

The operation is as follows; main valve 22 is moved across the valve seat 11 by aux-

iliary piston 17 to control the delivery of steam to and from the main cylinder. The delivery of steam to and from the auxiliary cylinder ends for movement of the auxiliary piston is controlled by auxiliary valve 20, moved by connections to the main piston rod, the auxiliary exhaust passing through port and passage 5, ports 9, 7 and passage 8 to the main slide valve exhaust cavity 23

55

10 for discharge with the main cylinder exhaust.

In the modification shown in Figs. 3 and 4 the main valve 22 is provided with a single elongated projection 29 which fits within a suitable recess 30 in the connecting portion 18 of the auxiliary piston 17. Projection 29 is provided on one side with a port *a* registering with a port *b* in the corresponding side wall of recess 30, the port *b* connecting 20 with the auxiliary exhaust port and passage 5 and the port *a* connecting with the exhaust cavity 23 of the main valve through a passage *c*. As in the first construction the ports *a* and *b* are provided with flaring 25 openings and are held in steam tight engagement by spring 31 bearing against projection 29 and the side wall of the recess 30, and secured to the main valve by screw 32.

60

What is claimed is:

30 1. In a steam engine valve, the combination with a main valve, an auxiliary piston for moving the main valve, an auxiliary valve controlling the movement of the auxiliary piston, and an auxiliary exhaust passage through the auxiliary piston, of a side port in the auxiliary piston connecting with the auxiliary exhaust passage, a projection on the main valve, a side port in the projection registering with the first mentioned 35 port and connected to the main valve exhaust cavity, and means for holding the ports in steam tight engagement.

65

2. In a steam engine valve, the combination with a main valve, an auxiliary piston for moving the main valve, an auxiliary valve controlling the movement of the auxiliary piston, and an auxiliary exhaust passage through the auxiliary piston, of a side port in the auxiliary piston connecting with 40 the auxiliary exhaust passage, a projection on the main valve, a side port in the projection registering with the first mentioned port and connected to the main valve ex-

70

haust cavity, and resilient means for holding the ports in steam tight engagement. 55

3. In a steam engine valve, the combination with a main valve, an auxiliary piston for moving the main valve, an auxiliary valve controlling the movement of the auxiliary piston, and an auxiliary exhaust passage through the auxiliary piston, of a side port in the auxiliary piston connecting with the auxiliary exhaust passage, a projection on the main valve, a side port in the projection registering with the first mentioned 60 port and connected to the main valve exhaust cavity, resilient means for holding the ports in steam tight engagement, and flaring openings for the ports.

65

4. In a steam engine valve, the combination with a main valve, an auxiliary piston for moving the main valve, an auxiliary valve controlling the movement of the auxiliary piston, and an auxiliary exhaust passage through the auxiliary piston, of a side 70 port in one side of the auxiliary piston and connected to the auxiliary exhaust passage, projections on the main valve adapted to receive the auxiliary piston between them, a side port in one projection registering with the first mentioned port and connected to the main valve exhaust cavity, and resilient means between the other projection and the auxiliary piston for holding the ports in steam tight engagement. 75

80

5. In a steam engine valve, the combination with a main valve, an auxiliary piston for moving the main valve, an auxiliary valve controlling the movement of the auxiliary piston, and an auxiliary exhaust passage through the auxiliary piston, of a port 85 in one side of the auxiliary piston and connected to the auxiliary exhaust passage, projections on the main valve adapted to receive the auxiliary piston between them, a side port in one projection registering with the first mentioned port and connected to the main valve exhaust cavity, resilient means between the other projection and the auxiliary piston for holding the ports in steam tight engagement. 90

95

6. In a steam engine valve, the combination with a main valve, an auxiliary piston for moving the main valve, an auxiliary valve controlling the movement of the auxiliary piston, and an auxiliary exhaust passage through the auxiliary piston, of a port in one side of the auxiliary piston and connected to the auxiliary exhaust passage, projections on the main valve adapted to receive the auxiliary piston between them, a side port in one projection registering with the first mentioned port and connected to the main valve exhaust cavity, resilient means between the other projection and the auxiliary piston for holding the ports in steam tight engagement. 100

In testimony whereof, I have hereunto set my hand.

GEORGE P. ABORN.
